UNITED STATES PATENT OFFICE.

JULIUS J. LOHER, OF CHICAGO, ILLINOIS.

MULTIPLE SWITCH.

Application filed February 23, 1926, Serial No. 89,906. Renewed October 31, 1928.

My present invention relates generally to an electric switch and more particularly to the type known as a toggle-switch. Such a switch usually comprises a pair of terminals that are engaged and connected to form a circuit by means of a bell-crank contact or connector element that is pivoted at its apex and is operated by means of a small lever that projects through the wall plate to be manually moved by the operator. The bell-crank contact element is operatively connected to the lever in such manner that while the latter is being moved from one position to another, the connecting mechanism will pass the "dead-center" between the fulcrums of the lever and bell-crank and will cause the bell-crank to snap over to its other position.

So far as I am aware it is the usual practice to make and break a single circuit in switches of this character, but I have designed the structure so that a plurality of circuits may be controlled and any one or more may be used at will according to the selection made by the operator.

For the sake of simplicity I have illustrated my invention in connection with two circuits either of which may be formed by itself or both may be cut-in at the same time. I have provided very simple means for accomplishing the function just stated and I do this in a novel and dependable manner so as to not materially increase the cost of manufacture of the switch over the ordinary type of toggle-switch. Briefly stated, I utilize the standard type of switch and mount the bell-crank contact element upon a depressible carrier that is preferably hinged to the bridge-plate of the switch box, and position the additional terminal for the second circuit adjacent the out-going terminal or lead of the regular standard switch. I form notches upon an adjacent arm of the bell-crank to coact with a hooked or lipped end of the additional terminal so that after the first or initial circuit is formed the operator may depress the carrier to permit the bell-crank to rotate farther and thereby engage the additional terminal with one of the notches in the arm without engaging with the initial terminal. Further depression of the carrier permits further rotation of the bell-crank so that the notched arm leaves the initial terminal and engages only the additional terminal thus cutting out the first circuit and leaving only the second circuit in

use. A reverse movement of the operating lever moves the bell-crank to a position where it is disengaged from all of the terminals and the circuits closed. In other words a movement of the bell-crank connector member in one direction forms one circuit and its movement in another direction forms the succeeding circuit or circuits, and in this connection I prefer to have one of the arms constantly engaged while the other member of the bell-crank is moved to or past the opposite terminals.

I prefer to carry out my invention, and to accomplish the several objects thereof in substantially the manner hereinafter fully described and as more particularly pointed out in the claims, reference being made to the accompanying drawings that form a part of this specification, in which:

Figure 1 is a longitudinal side view of my improved switch, the adjacent wall of the box or casing being removed and the top or wall-plate omitted, the switch being shown in first position and operating the initial circuit.

Figure 2 is a similar view showing the second position assumed for cutting in two circuits.

Figure 3 is a similar view showing the first circuit broken and the second circuit remaining in use.

Figure 4 is a transverse vertical section taken on line 4—4 of Figure 1.

In the drawings similar reference characters are used to designate the same parts wherever they appear throughout the several views. The drawings are more or less schematic for the purpose of illustrating a typical or preferred embodiment of my invention which consists of a housing or casing of box-like form of insulating material and preferably of rectangular shape with one of the longitudinal walls omitted and across this open side of the box is placed a bridge plate 6 to carry the operating or movable parts of the switch. The lead-in terminal is an elongated metal strip suitably bent so that an attaching portion 7 is provided that is secured to an end wall of the box and has an inwardly and upwardly extended end portion 8 that provides a terminal to be engaged by the circuit forming element of the switch when the switch is operated. The opposite terminal member is a bent metal strip, a portion 9 of which is flat and straight and is secured against the bottom wall of the box

and has an upwardly and inwardly twisted portion 10 that is positioned in alignment with the terminal end 8 of the other strip. These terminal ends 8 and 10 are so positioned that the circuit forming element of the switch will engage the same when the switch is moved to its initial or first position as seen in Fig. 1. Each of the metal strips have portions that extend towards the plane of the bridge-plate 6 where they have lateral members 7 and 9 respectively into which the binding posts 11 and 12 are screwed. Another member has a flat straight portion 13 secured to the bottom wall of the box and extends to a position in the front of the terminal 10 where it is provided with an up-standing L-shaped end 14 that is positioned intermediate the terminals 8 and 10 and in the path of movement of the circuit forming element of the switch. The metal strip from which this last described terminal is formed extends upwardly from the bottom of the box in the plane of the bridge-plate 6 in an oblique stretch 15 and then has a horizontal lateral portion 16 into which its binding post 17 is screwed.

Adjacent the binding-post 11 the bridge-plate is provided with a transverse slot 18 to receive the L-shaped angular end 19 of a carrier plate 20, the opposite end of which carrier is bifurcated so as to extend upon each side of a guide bracket and stop 21 secured to and projecting inwardly from the underside of the bridge-plate 6. The normal position of the carrier plate is flat against the underside of the bridge-plate and it is maintained yieldingly in this position by means of a flat spring 22 secured at one end to the bridge plate and at its opposite end presses against the carrier-plate. The carrier-plate is provided centrally with a tubular embossment 23 that projects through an opening 24 (Fig. 3) in the bridge-plate 6, and pivoted on a pin 25 secured in opposite walls of the embossment is an oscillatory lever 26 that is moved back and forth upon its pivot to operate the circuit forming element of the switch. Below the carrier-plate 20 is an oscillating or rocking plate 27 that is mounted at its opposite sides in suitably shaped parallel brackets 28, 28, depending from the carrier plate. A bell-crank, consisting of substantially right angular arms 29 and 30, is secured to lugs projecting from the oscillating member, and as detailed in Fig. 4 these arms are formed from two thin pieces of metal that are spaced apart slightly at the outer ends of the arms as at 31 to permit these pieces of metal to pass upon each side of the terminal ends 8 and 10 and insure a wiping contact when engagement is made. Means are provided for operatively connecting the lever 26 with the oscillating plate, which means includes the usual spring-operated plunger structure 32, so that whenever the lever is

moved on its pivot to either of the positions indicated in Fig. 1 the oscillating plate 27 will be moved to an opposite position and this moving is done by a snap movement, so that a quick make and break is effected in the manner usual with the well known toggle-switch, and the spring exerts its tension to maintain the bell-crank and oscillating plate in the position into which it has been moved and prevent accidental dislodgment.

After the switch has been moved to the initial or first position shown in full lines in Fig. 1, it may be desired to include the second circuit while still maintaining the first circuit and this may be done by pushing inwardly or depressing the lever so as to cause a slight hinging of the carrier-plate 20 which bodily moves the movable switch elements in an arc struck from the hinge end of the carrier. The end of the bell-crank arm 30 is enlarged or provided with a head and back of this head is a series of notches or recesses 33 so that the bodily movement of the bell-crank as just described will permit the head to ride past the adjacent portion of the L-shaped terminal 14 and permit the notch nearest the head to engage with the edge of the terminal while the head is still engaged with the terminal 10 as shown in Fig. 2. Thus the lead-in terminal 8 is in electrical connection with both terminals 10 and 14 and two sets of lamps for example will be lighted. Further depression of the lever 26 and consequent hinging of the carrier 20 with the switch elements thereon will cause the arm 30 to disengage the terminal 10 and the next or second notch in arm 30 of the bell-crank will engage the edge of terminal 14 so that the circuit through the latter is maintained by itself as designated in Fig. 3. By swinging the lever 26 upon its pivot 25 to its opposite position, indicated in dotted lines in Fig. 1, the bell-crank will return to its normal position and all the circuits will be broken. Should it be desired to initially throw in the second circuit through terminal 14, this may readily be done by first depressing the lever 26 as far as the carrier plate 20 will permit and then snapping the switch by swinging the lever 26 on its pivot while holding the structure depressed. This will cause the arms 30, when the bell-crank operates to move past terminal 10 to the position shown in Fig. 3 and the second notch will engage terminal 14.

The switch I have devised is especially applicable for use in rooms or other apartments in which a plurality of lights are installed and where it is desired to turn on one or more or all of the lights and the same may be readily selected by the proper manipulation of this switch which avoids the use of "gang" switches such as are now used in which there are a plurality of buttons or levers to operate. It may also be used in connection with the lights on motor vehicles, which as

is well known, are operated by selective rotation of a switch key or by a plurality of buttons. I have disclosed only a simple form in which my switch may be made, for it will be obvious that slight changes may be made to increase the number of circuits operated without departing from the principles I have disclosed herein, and it will be understood that such changes are fully contemplated as coming within the scope of the appended claims.

What I claim is:—

1. A switch comprising a plurality of terminals one of which is common to the others, and a contact member normally disengaged from all of said terminals, said member movable in one direction to connect the common terminal with one of the other terminals and movable in another and different direction to connect said common terminal with another of the other terminals while the member remains in contact with the first connected terminals.

2. A switch comprising a plurality of terminals, a terminal common to the first-mentioned terminals, and a contact member normally disengaged from all of said terminals, said member movable in one direction to connect one of said first-mentioned terminals with said common terminal and movable in a direction transverse to its first-mentioned movement to connect another of said first-mentioned terminals with said common terminal while the member remains in contact with the first connected terminals.

3. A switch comprising a plurality of terminals, one of which is common to the others, and a contact member normally disengaged from all of said terminals, said member movable in directions transverse to each other whereby the common terminal is adapted to be connected with any one or more of the other terminals at the same time to form a plurality of circuits through said member.

4. A switch comprising a plurality of terminals, a terminal common to the first-mentioned terminal, and a contact member normally disengaged from all of said terminals, said member having pivotal movement to connect the common terminal with one of the first-mentioned terminals, and bodily movable in a different direction to connect said common terminal with another of said first-mentioned terminals while the member remains in contact with the first connected terminals.

5. A switch comprising a plurality of terminals, a terminal common to the first-mentioned terminals, a pivoted contact member normally disengaged from all of said terminals, said member movable upon its pivot to connect said common terminal with one of said first-mentioned terminals, and an oscillatory carrier for said contact member the

movement of which causes said contact member to connect another of said first-mentioned terminals with said common terminal while the member remains in contact with the first connected terminals.

70

6. A switch comprising a plurality of terminals, a terminal common to the first-mentioned terminals, a plate hinged adjacent said terminals and movable towards and away from the same, and a contact member pivotally mounted on said plate whereby the pivotal movement of said member connects the common terminal with one of said first-mentioned terminals and the hinging movement of said plate causes said member to connect said common terminal with another of said first-mentioned terminals.

80

7. A switch comprising a plurality of terminals, a terminal common to the first-mentioned terminals, a contact member normally disengaged from all of said terminals, said member movable in one direction to connect the common terminal with one of the first-mentioned terminals, and means upon which the member is mounted and adapted to move the member in a direction transverse to its first-mentioned movement to connect the common terminal with another of said first-mentioned terminals while the member remains in contact with the first connected terminals.

85

8. A switch comprising a plurality of terminals, a terminal common to the first-mentioned terminals, a contact member normally disengaged from all of said terminals, said member movable in one direction to connect the common terminal with one of the first-mentioned terminals, and movable in another and different direction while engaged with said terminal to connect the latter with another of the first-mentioned terminals.

90

9. A switch comprising a plurality of terminals, one of which is common to the others, and a contact member normally disengaged from all of said terminals, said member movable in directions transverse to each other after being engaged with the common terminal and another terminal whereby to connect the common terminal also with any one or more of the remaining terminals.

105

10. A switch comprising a plurality of terminals, and a contact member normally disengaged from all of said terminals, said member movable in one direction to connect a pair of said terminals and movable in another and different direction to connect another terminal with one of said pair whereby a plurality of the other terminals may be simultaneously connected with the common terminal.

110

11. A switch comprising a plurality of terminals, and a contact member normally disengaged from all of said terminals, said member movable in directions transverse to each other whereby one movement will con-

130

nect a pair of said terminals and the other movement will connect another terminal with one of said pair while the first pair are connected.

5 12. A switch comprising a plurality of terminals, and a contact member normally disengaged from all of said terminals, said member having pivotal movement to connect a pair of said terminals and being bodily 10 movable in a different direction to connect another terminal with one of said pair while the first pair are connected.

15 13. A switch comprising a plurality of terminals, an oscillating contact member normally disengaged from all of said terminals, said member movable upon its fulcrum to connect a pair of said terminals, and a hinged carrier upon which said contact member is pivoted the movement of which carrier bodily 20 moves said contact member to connect one one of said pair of terminals with another terminal.

25 14. A switch comprising a plurality of terminals, and a contact member normally disengaged from all of said terminals, said member movable in one direction to connect a pair of said terminals and movable in an-

other and different direction while engaged with one of said pair of terminals to connect the latter terminal with another terminal.

30

15. A switch comprising a plurality of terminals, a contact member normally disengaged from all of said terminals, said member movable in directions transverse to each other one of said movements being made 35 after a pair of terminals have been engaged whereby to connect one of said pair of terminals with another terminal.

16. A switch comprising a plurality of terminals, a terminal common to the first-mentioned terminals, an oscillating support, and a contact member pivotally mounted upon said support and normally out of engagement with all of said terminals whereby the pivotal movement of said member connects 45 the common terminal with one of the first-mentioned terminals and the movement of said support causes said member to connect said common terminal with another of the first-mentioned terminals.

50

Signed at Chicago, in the county of Cook, and State of Illinois, this 18th day of February, 1926.

JULIUS J. LOHER.
